Primary Examiner — Philip S Hyder*Assistant Examiner* — Linda G. Brooks(74) *Attorney, Agent, or Firm* — Thompson Coburn LLP(57) **CLAIM**

The ornamental design for a cooling tower fan motor, as shown and described.

DESCRIPTION

FIG. 1 is a perspective view of a cooling tower fan motor showing our new design;

FIG. 2 is a top view of the cooling tower fan motor of FIG. 1; FIG. 3 is a right side view of the cooling tower fan motor of FIG. 1;

FIG. 4 is a left side view of the cooling tower fan motor of FIG. 1;

FIG. 5 is a front view of the cooling tower fan motor of FIG. 1; and,

FIG. 6 is a rear view of the cooling tower fan motor of FIG. 1.
